FRANZ PUENING, OF O'HARA TOWNSHIP, ALLEGHENY COUNTY, PENNSYLVANIA

METHOD OF AND APPARATUS FOR PRODUCING COKE

Application filed April 7, 1928. Serial No. 268,204.

My invention relates to apparatus for producing coke and particularly to coking apparatus that is adapted for use in the low-temperature distillation of coal, shale and other carbonaceous materials.

The coking apparatus of the present invention is similar in certain respects to the apparatus constituting the subject-matter of my copending application Serial No. 211, 10 887, filed August 10, 1927 (Case No. 68).

An object of my invention is to provide coking apparatus employing hot gases for heating a heat-storage member and in which the heating gases are effectually sealed from 15 the gases of distillation.

A further object of my invention is to provide coking apparatus in which coal in its plastic state is prevented from adhering to surfaces other than those of the source 20 of carbonizing heat.

A further object of my invention is to provide coking apparatus in which improved means, such as a porous layer of material, are employed for facilitating the passage 25 and collection of the gases of distillation.

A still further object of my invention is to provide an efficient and durable means for elevating fine coke or coke breeze that is employed in connection with the coking 30 operation.

In the operation of coking apparatus of the continuous type, in which heat-storage members pass successively through a heating chamber and a coking chamber, considerable difficulty has been experienced in maintaining the separation of the gases of combustion ordinarily employed for heating the apparatus and the gases of distillation of coal or other material being treated.

If the gases of distillation are permitted to mingle with the waste gases, valuable products of the coking operation are lost. If the waste gases are permitted to mix with the gases of distillation, the latter are diluted and undesirable products are combined therewith.

In accordance with the present invention, I provide low-temperature distillation apparatus comprising a hollow cylindrical member that is mounted for rotation about its

horizontal axis. The outer surface of the hollow member passes through two zones, one in which heat is stored in metallic ribs and a second zone in which the stored heat is employed to carbonize coal or other material to be treated that has been placed in the narrow grooves between the ribs. Inasmuch as the hollow member is constantly rotating and its surface is successively employed for the operations of storing and giving off heat, it is essential that the heating zone be separated from the distillation zone in order to separate the respective gases therein.

It has been particularly difficult to seal the two zones or chambers against each other at the place where the rotating member passes from the coking chamber back into the heating chamber, because it is at this place that the coke must be removed. The coke-removing means obstruct any mechanical means that may be employed for sealing the chambers against each other at this point. The action of the coke at this place where it is being removed from the coking spaces presents another difficulty, because coke often has shrunk in volume considerably, so that the sealing means would have to extend into the cracks opened up by the shrinkage of the coke.

The coke may have shrunk so much that it falls out of the spaces in which it was contained before it approaches the coke-removing devices so that it is necessary to seal against a series of coking spaces, which are only partly filled with coke and this is difficult. The particular means employed for sealing at this difficult point is a supply of fine coke or fine breeze, which is supplied to the dividing line between the two chambers in such manner that it bridges over from the surrounding housing to the rotating hollow member. The fine dust presses against the rotating hollow member and fills every crevice in the coke or in the surface of the member, whether small or large.

In the arrangement as shown, the supply of fine dust is introduced at a point of such elevation that the dust stands even above the line in which the coke scrapers are lo-

cated and thus completely surrounds them, the dust entering the empty spaces which were just previously filled with coke. In this manner, the coke scrapers are protected against the high heat of the heating gases. However, this location of the supply point for fine coke relative to the scrapers is not essential and the scrapers could be located above the point of coke supply.

10 The supply of fine coke or breeze is also continuously supplied to other surface portions of the hollow member between the distilling zone and the heating zone, for instance, across the ends of the hollow member.

15 Another portion of the coke breeze is employed in the form of a layer superposed on the coal to be treated and this layer of fine coke serves two purposes. It provides a path of fairly low resistance for the escape 20 of gases of distillation toward the outlets therefor and it prevents the coal when it reaches a plastic state from adhering to the means for retaining the coal on the outer periphery of the rotating hollow member.

25 These several supplies of fine coke, serving for different purposes, finally mix with the coke produced by the apparatus whereupon the coke breeze is separated from the coke produced and is returned to the various 30 points from which it is distributed to the several parts of the hollow member to be used as a seal, as described above.

An elevating mechanism that is provided 35 for the purpose of elevating the coke dust for distribution to the several points from which it is supplied is particularly designed for use in connection with materials at fairly high temperatures. In general, the elevating mechanism comprises a series of overlapping wheels each of which has recesses in a circumferential ring that are adapted 40 to receive material in their lower positions and to discharge the same in their upper positions to the wheel or other receiving 45 device that is next in the series. The wheels are enclosed in a casing and the shafts, by means of which the wheels are supported, extend through the side walls of the casing and their bearings are outside whereby they 50 are not subjected to the heat of the material supplied to the elevating mechanism.

Reference may now be had to the accompanying drawings, in which

55 Figure 1 is a view in transverse vertical section, taken on line I—I of Fig. 2;

Fig. 2 is a view, partially in elevation and partially in section, along the line II—II of Fig. 1;

Fig. 3 is a view similar to Fig. 1 of a 60 modification; and

Fig. 4 is an enlarged view in vertical section of a portion of the elevating mechanism of Fig. 3.

Referring particularly to Figs. 1 and 2, 65 the coking apparatus of my invention com-

prises a horizontal cylindrical shell 1 of metal that is mounted for rotation about its horizontal axis and has associated therewith an endless flexible chain 2 that is movable with the shell 1 for a portion of its circular path of movement. The chain 2 is mounted upon suitable rollers 3, 4, 5 and 6. A housing 7 encloses the lower portion of the hollow shell 1 that is associated with the chain 2 for the purpose of confining the gases of distillation in order that the latter may be collected through suitable outlet pipes 8.

The upper portion of the shell 1 extends into an enclosure 9 which may be of suitable refractory material that is adapted to be supplied with hot gasses which may be, for example, gases of combustion, through a flue or duct 10. The gases pass over the upper portion of the shell 1 and are then conducted through a flue 11 to a stack or other suitable means for disposing of them.

A hopper 13, which extends throughout the length of the rotating shell 1, supplies coal to be carbonized to the heated outer surface of the latter. An adjacent hopper 14 of similar extent supplies relatively fine coke or coke breeze in a layer that is superposed on the layer of coal, as will be more fully described. The fine coke is preferably preheated above the temperature above the condensing point of the volatile matter in the coal.

A hopper 15 that is substantially diametrically opposite to the hoppers 13 and 14 supplies coke breeze to the portion of the shell 1 that is between the heating zone and the coking zone in order to maintain separation between gases in their respective zones. Coke breeze from the same source also fills the spaces at the ends of the shell 1 between the latter and the end of the casing 7.

The shell 1 comprises a hollow cylindrical member 17 that is provided with circumferential metallic ribs 18 having relatively narrow spaces therebetween for the reception of the material to be carbonized. These ribs 18 are shown in Fig. 2. The outer member 17 is connected by a series of non-radial spokes 19 to an inner shell 20. The shell 20 is connected at its outer ends by means of disks 21 to a shaft 22 which constitutes a rotatable support for the entire structure of the rotatable shell 1. The structural details of the shell 1 constitute no part of the present invention, since they are the subject-matter of claims of the copending application referred to hereinabove.

An elevating mechanism 24 that is employed in connection with the coking apparatus comprises a series of overlapping wheels 25 that are mounted on horizontal shafts 26, the wheels 25 being enclosed by a casing 27 through which the shafts extend. The shafts 26 are provided with suitable

bearings 28 (Fig. 3) that are outside the casing 27 whereby they will not be subjected to the relatively high temperatures that obtain within the interior of the casing by reason of the nature of the materials handled thereby.

Each of the wheels 25 is provided with an annular portion having inwardly opening inclined pockets or recesses 23 for receiving the coke breeze or other material to be handled thereby and which will be discharged from such pockets when they reach substantially the uppermost position of the coal. Inasmuch as the wheels overlap, the lower portion of an upper wheel is below and in a position to receive the material from the uppermost position of the lower wheel, chutes or hoppers 29 being provided between the overlapping portions for guiding the material during the transfer from one wheel to another.

As is shown in Figs. 1 and 2, the uppermost wheel in the series discharges its material into a hopper 30 from which it is distributed, as will be later described. The remaining details of the apparatus of Figs. 1 and 2 will be described in connection with the operation of the latter in distilling or coking coal.

It may be assumed that hot gases of desired temperature are circulated through the refractory enclosure 9 by means of the flues 10 and 11. It may be assumed further that the heat storage portion of the shell 1 has been heated to such temperature that coal in contact therewith will be distilled to low-temperature coke upon its passage through the coking zone, which is indicated by the portion of the flexible chain 2 that is adjacent to the shell 1.

The shell 1 which, as viewed in Fig. 1, rotates in a clockwise direction, is supplied with coal from a hopper 31 and which is distributed to the hopper 13 along the length 45 of the shell 1 by means of a screw conveyor 32. A relatively thin layer of coal is deposited by the hopper 13 along the surface of the wheel between the heated ribs 18.

Coke breeze from the hopper 30 is supplied to horizontal screw conveyors 33 and 34, the latter being transverse to the axis of the wheel 1 and which in turn supplies a similar conveyor 34a that distributes the coke breeze along the shell 1 for distribution by the hopper 14. The coke breeze is supplied in a relatively thin layer that is superposed on the layer of coal and is adjacent to the chain 2. This layer of coke breeze prevents the coal from adhering to the chain 2 and also provides a relatively porous path outwardly for the gases of distillation. The coke is sufficiently heated that distillates do not condense thereon. The latter are withdrawn through the series of outlets 8, to which a desired degree of suction

may be applied by any usual or suitable means (not shown).

When the finished product and the layer of fine coke arrive at an elevation slightly above the roller 4, they are carried outwardly by the chain 2 and discharged on a screen 35. If, however, any of the coke fails to fall from the shell 1 by force of gravity, it is removed from the spaces between the ribs by means of a series of scrapers 36.

The scrapers 36, which are on the dividing line between the heating zone and the coking zone, are supported by a pipe 37, the scrapers having a wide upper end to prevent their falling out of position. The lower end 80 of each of the scrapers 36 is notched to receive a bar 38 which limits its upward movement. The bars 38 are secured to a rotatable bar 39 having a handle 40 by means of which the bars 38 may be adjusted. The scrapers 36 are surrounded by a body of coke breeze that is supplied from the hopper 30 by means of the screw conveyor 33 and the hopper 15.

Inasmuch as the difference in pressures 90 between the heating zone and the distillation zone are maintained relatively small by suitable regulation, the relatively thick body of coke breeze adjacent to the scrapers 36 and which extends across the lower portion 95 of the end surfaces of the shell 1 offers sufficient resistance to the passage of gases therethrough to prevent any material intermingling of the gases.

The coke produced by the apparatus and 100 the fine coke that has been supplied thereto are separated by the screen 35, the larger lumps of coke passing down an inclined portion of the casing 7 to coke-discharge wheels 41. The fine coke which passes through the 105 screen 35 is carried by a horizontal screw conveyor 42 to the lower wheel 25 of the elevating mechanism 24, which operates continuously to transfer the coke breeze to the hopper 30 in the manner previously described.

The excess fine coke may be removed as it accumulates in the bottom of the casing 27.

It may occur that the coke breeze supplied to the conveyors 33 and 34 is at times in excess of their capacities. Overflow chutes 43 and 44, respectively, return such excess quantities to the conveyor 42 for recirculation.

From the foregoing description, it will be noted that the process of supplying coal and fine coke to the coking apparatus is continuous and that the products, including the gases of distillation and the resultant low-temperature coke, may be continuously withdrawn from the apparatus. The coke breeze is recirculated for the purpose of preventing the adherence of the plastic coal to the retaining device and for providing a seal 130

between the heating zone and the coking zone.

Inasmuch as a certain amount of coke breeze or coke dust will be produced by the 5 apparatus, amounts must be withdrawn when necessary in order to reduce the excess.

Reference may now be had to Fig. 3, in which a modification is illustrated. Similar 10 reference numerals are employed to designate parts corresponding to those of the apparatus of Figs. 1 and 2. This arrangement differs from that previously described, in that a stationary guide member 45 is substituted for the movable flexible chain. A heating zone is provided by means of an enclosure 46 of refractory material that is supplied with an inlet opening 47 for hot gases and an outlet flue or duct 48.

20 Scrappers 49 adjacent to the lowermost portion of the shell 1 remove such coke as may adhere to the shell 1 and their supporting framework 50 is provided with a water seal 51 for the purpose of preventing the escape 25 of gases through this portion of the structure. The stationary guide member 45 is provided with two openings communicating respectively, with passageways 52 and 53 that are connected to gas mains 54 and 55.

30 Additional heating means that is effective during the coking operation comprises a refractory enclosure 56 for surrounding the guide member 45 and which is provided with an inlet opening 57 for hot gases.

35 These hot gases traverse a path indicated by arrows and which path includes a duct 58 around the main 55 and an outlet duct 59 which leads to a flue 60.

The operation of the modified form of 40 my invention is similar in most respects to that of the apparatus previously described. Coal is supplied to an upper portion of the shell 1 by means of a hopper 62 that extends throughout the length of the shell 1. A 45 hopper 63 supplies a layer of fine coke that is superposed on the layer of coal and that is adjacent to the stationary guide member 45. During the passage of the coal through 50 the coking zone, gases of distillation are withdrawn through the gas mains 54 and 55, the layer of coke permitting the gases of distillation to travel along the guide member 45.

The hot gases supplied to the guide member 45 may be regulated, as desired, to supplement the heating of the shell in the heating zone. The relative degrees of suction applied to the mains 54 and 55 may be varied as desired to insure the withdrawal 60 of substantially all of the gases of distillation without also withdrawing waste gases from the adjacent spaces to which the latter are supplied.

The mixture of low-temperature coke and 65 coke breeze is discharged at substantially

the lowermost portion of the shell 1 upon a screen 64 for separating the coke breeze from the larger lumps of coke. The coke breeze which passes through the screen is carried by a horizontal conveyor 65 to an 70 inclined screw conveyor 66 which empties into an elevator mechanism 67 which is identical in material respects with that of Figs. 1 and 2 but differs therefrom in certain details to be later described. The coke breeze at the top of the elevating mechanism is received by a hopper 68, from which it is distributed to the hopper 63 by a screw conveyor 69.

While ordinarily the coke breeze being recirculated will retain a considerable portion of its heat, it may be desired to preheat or superheat it while passing through the elevator mechanism and for this purpose the casing 27 is provided with an inlet opening 70 for the admission of hot gases to its interior. If desired, the coke breeze may be preheated while in the hopper 68 by means of hot gases entering through a duct 71 and passing out through a flue 72 in the 80 top of the elevator casing.

Referring to Fig. 4, in which certain of the details of the elevator mechanism 67 are shown, the lowermost wheel 25 is provided with scoops or buckets 74 for the purpose of collecting any coke dust in the bottom of the casing 27 as the result of spillage. The scoops 74 empty into the lower hopper 29 when at approximately their uppermost positions. The side walls of the casing 27 are provided with extensions 75 to provide space for the rotating buckets 74.

While I have described fine coke or coke dust as the preferred sealing means by reason of its being available in connection with the manufacture of coke, it will be appreciated that other sealing means may be employed. For example, under certain conditions where the local temperatures are sufficiently low or where the coal is non-coking, coal dust may serve as the sealing medium without the coal becoming plastic. Such coal may also be used as preheated coal to be supplied to the coking apparatus after serving as a sealing medium.

The arrangement for covering the layer of coal to be coked with a layer of fine coke which layers are under considerable pressure by the belt 2 in Fig. 1 or the stationary guide 45, Fig. 3, insures that the coke produced will be firm and strong. Such would not be the case if the coal were merely loosely held in the slots between the ribs.

The apparatus of my invention operates continuously and substantially automatically 125 to produce low-temperature coke economically and at a rapid rate by reason of the thin layers of coal between members which quickly transfer heat to the coal. The gases of distillation are collected by suitable means 130

and they are effectually separated from waste gases to prevent loss or dilution. The foregoing and other advantages will be apparent to those skilled in the art.

5 The apparatus of my invention may be variously modified. For example, a combination may be made in which the coal and coke is retained in the spaces between the ribs for part of its travel by a chain 10 or chains as shown in Fig. 1 and for another part of its travel by a heated retaining shield as shown in Fig. 3. The pressure which is exerted by the retaining chain, or by the retaining wall against the wheel, may be varied by various means, as for instance, the weight of the idler which rests in the lower loop of the chain. Also, the wheel may have 15 ribs of different types or it may be smooth.

It is understood that the scope of my invention is not limited except as expressed in 20 the claims.

I claim as my invention:

1. The combination with two spaced movable members, one of said members being 25 adapted to be heated to coke coal in contact therewith, and means for supplying a layer of coal to the heatable member and a layer of fine coke superposed on the layer of coal and in contact with the other member, of a source of heating gases for heating 30 said heatable member, means for discharging the resultant product of said heatable member and said fine coke from said heatable member, and means for supplying fine 35 coke adjacent to said discharging means and so as to constitute a seal by the fine coke between the heating gases and the gases of distillation of said coal.

2. The method of coking coal by means of 40 a moving heat-storage device which comprises supplying coal to a portion of the surface of said device to be treated during a portion of its path of movement, supplying hot gases for heating said device to coking 45 temperature during another portion of its path of movement, the coal and heating gases being applied to the same surface of the device, coking the coal on the device by heat previously absorbed thereby and supplying 50 solid granular material infusible at the coking temperature for sealing said device between the different portions of its path of movement to prevent interchange of heating gases and gases of distillation.

55 3. The method of carbonizing coal or the like by means of a moving heat-storage device which comprises supplying coal to a portion of the surface of said device to be carbonized during a portion of its path of 60 movement, supplying hot gases for heating said device to carbonizing temperature during another portion of its path of movement, the coal and heating gases being applied to the same surface of the device, coking the coal on the device by heat previously

absorbed thereby, sealing said device between the different portions of its path of movement with fine carbonized material to prevent interchange of heating gases and 70 gases of distillation and substantially enclosing the material being carbonized with the sealing material.

In testimony whereof, I have hereunto subscribed my name this fifth day of April 1928.
